UNITED STATES PATENT OFFICE.

EDNA SIBLEY TIPTON, OF NEW YORK, N. Y.

SHOPPER'S NAIL CLEANING AND POLISHING SET.

Application filed September 16, 1924. Serial No. 738,009.

To all whom it may concern:

Be it known that I, EDNA SIBLEY TIPTON, citizen of the United States, residing at New York city, in the county of New York and State of New York, have invented certain new and useful Improvements in Shopper's Nail Cleaning and Polishing Sets, of which the following is a specification.

The object of this invention is, to supply a small, neat, compact and ornamental nail cleaning and polishing set, suitable for carrying in a lady's hand bag or in a man's pocket.

Said set consists of certain elements or members arranged to be assembled into a single, self-contained unit, which comprises a nail-polish container, a nail-bleach container, a nail-stick and a file; one of said members is adapted to carry a buffing material.

The construction of my improved nail cleaning and polishing set is fully described in the following specifications and is also illustrated in the accompanying drawings, in which:

Figs. 1 to 6 illustrate one form of my device, which, for the purposes of this specification, will be termed the preferred form and Figs. 7 to 14 illustrate a modified form. Neither of these forms can be said to have material preference over the other, and the main reason for the modification lies in the fact that one form is better adapted to contain certain kinds of manicure material than the other; furthermore, one form may be somewhat better adapted to be made of such material as bakelite, hard rubber, celluloid, and similar material, and the other form, somewhat better adapted to be made of metal.

The various figures of the drawings are as follows:

Fig. 1 is a side view of my improved nail cleaning and polishing set.

Fig. 2 is an end view of same.

Fig. 3 is a central, longitudinal section.

Fig. 4 is a transverse section.

Fig. 5 is a bottom view of the case.

Fig. 6 is a side view of the closure or cork for the ends of said case.

Fig. 7 is a side view of a modified form of my set.

Fig. 8 is an end view of said modified form.

Fig. 9 is a transverse section of same.

Fig. 10 is a longitudinal section of said modified form.

Figs. 11 and 12 are end and side views respectively of a combined closure and container member which may be used in either form here shown.

Fig. 13 is a bottom view of said modified form.

Fig. 14 is an end view of the buffer member of the modified form with the buffer material removed therefrom.

The construction of said preferred form, as illustrated in said Figs. 1 to 6 will be first described; it is however, pointed out, that a description of either form may apply generally to both.

This construction comprises a tubular body or case 1, having upon one side thereof a longitudinally-disposed extension 2, arranged for the removable carrying or attachment of a buffer member 3, which is adapted to receive and carry a buffer material 4, such as felt or chamois skin.

Said buffer member 3 is removably attached to or carried by the lower face of said extension 2 preferably by means of a T-slot 5, and in case a T-slot is selected, said buffer member is supplied with a co-operating T-head 5' (see Fig. 14) adapted to slide longitudinally in said T-slot. It will be readily understood that any other form of securing device may be substituted for said slot.

The bore of said tubular body or case 1 extends entirely through said body, and one end of said bore is supplied with a removable closure member 6, which is also bored out from its inner end to receive and hold one end of a stick 7 of nail-polish. The other end of said case is also provided with a removable closure element for said bore, as shown at 8, and which may be identical in form and construction with the element 6, or it may differ therefrom, in accordance with the particular function for which it is employed. As shown in Fig. 3, however, it contains a substance 9 that is known in the manicure art as nail-bleach, a substance having the characteristics of an amorphous wax, and is retained within the chamber 100 of the closure member by reason of its own cohesive and adhesive nature. If it is desired to provide this closure element with a closure at its inner end, this may be done in accordance with the illustration Fig. 12, 110

in which 17 represents the closure element for the container 16.

In case a partition is desired in the bore of case 1, this may be supplied in the form of a close-fitting cork disc 10, which has the advantage of being adjustable longitudinally of the bore in which it fits, and may be positioned longitudinally thereof as required.

10 Said extension 2 is provided with a receptacle or chamber 11, for the reception of manicure accessories such as a nail-stick 12, also a nail-file if desired. Said receptacle is so formed and positioned that said buffer member 3 forms a cover or closure therefor and thus serves to retain within said receptacle, 11, such accessories as may be placed therein.

15 In this form of my device a nail-file, or its equivalent is preferably carried at 13 between case 1 and said member 3.

20 The modified form of construction illustrated in Figs. 7 to 14, differs in one respect from the previously-described, Fig. 1 form 25 in the fact that the dimension "a" in the modified, or Fig. 7 form is shorter than the corresponding dimension "a" in the Fig. 1 form, and the container 11 is transposed to the buffer member 3.

25 Inasmuch as many of the reference numerals of the foregoing description may be applied to identical parts of the modified form, they will be so employed in the following description of said modified form as follows:

30 The reference numeral 1 represents the tubular case, the reference numeral 2 indicates the buffer extension, 3 the buffer member, 4 the buffer material, 5' the T-head of 35 said buffer member, and 11 the container, which, as previously stated is in said member 3.

35 In this modified form the closure elements 14 and 15 for the bore of case 1 are made in 40 the form of tubular containers, as illustrated in Figs. 10 and 12. The tube or body 16 of these closure-containers may vary in length if required, and the inner, open end of each may be supplied with a cork or closure 17. 45 This form of closure-container is especially 50 adapted to carry a nail-polish in the form of a powder. Their construction is such as to adapt them to contain and carry a liquid if desired.

55 In this modified form of buffer member, 55 the buffer material 4 is shown as being secured to the member 3 by means of a metal band or hoop 18.

Reference is hereby made to my co-pending application for a patent on a shopper's 60 nail cleaning and polishing set, Serial No. 725,884, filed on the 14th day of July, 1924.

I claim the following:

1. A shopper's nail cleaning and polishing set comprising a tubular case having a bore 65 extending therethrough, a tubular closure element removably carried in each end of said bore, a longitudinally-disposed extension formed upon one side of said case arranged to carry a buffer member, a buffer 70 member removably carried by said extension, said case and said buffer member being adapted and arranged to conjointly form, when assembled, a receptacle for the reception and retention of manicure accessories. 75

2. A shopper's nail cleaning and polishing set comprising a tubular case having the bore thereof extending therethrough, a tubular closure element removably carried in each end of said bore, each of said closure 80 elements being adapted to contain a manicure accessory, a longitudinally-disposed lateral extension upon one side of said case adapted to carry a buffer member, a buffer member removably carried by said extension, said case and said buffer member being 85 adapted and arranged to conjointly form, when assembled, a receptacle for the reception and retention of manicure accessories.

3. A shopper's nail cleaning and polishing 90 set comprising a tubular case having a bore extending longitudinally therethrough, an adjustable partition adapted to divide said bore longitudinally into two compartments, a tubular closure element removably carried 95 in each end of said bore, each of which is adapted to contain a manicure accessory, a longitudinally-disposed, lateral extension formed upon one side of said case arranged to carry a buffer member, a buffer member 100 removably carried by said extension, said case and said buffer member being adapted and arranged upon assembly to jointly comprise a receptacle for the reception and retention of manicure accessories, when said 105 set is carried in a hand bag or a pocket.

In testimony whereof I affix my signature.

EDNA SIBLEY TIPTON.
